UNITED STATES PATENT OFFICE.

FERNANDO G. MILLER, OF FORT MYERS, FLORIDA.

FISH-SEINE FABRIC.

1,217,978.

Specification of Letters Patent.

Patented Mar. 6, 1917.

Application filed July 24, 1913. Serial No. 781,017.

To all whom it may concern:

Be it known that I, FERNANDO G. MILLER, a citizen of the United States, residing at Fort Myers, in the county of Lee and State of Florida, have invented certain new and useful Improvements in Fish-Seine Fabrics: and I do hereby declare the following to be a full, clear, and exact description of the invention, such as will enable others skilled in the art to which it appertains to make and use the same.

This invention relates to new and useful improvements in seine fabric and has for its object the provision of a device of the above 15 character which may be constructed of metal and thereby render the same substantially indestructible.

Another object of my invention is the provision of such a device which will be so constructed as to retain its flexibility, thereby permitting it to be folded into substantially the same space as would be occupied by the ordinary type of seine.

A still further object of my invention is 25 the provision of a device which will materially lighten the construction of seines and render them more easily handled.

With the above and other objects in view I now proceed to describe my invention in 30 the following specification and accompanying drawings, in which,

Figure 1 is a plan view of a portion of my improved seine fabric showing the method of construction,

Fig. 2 is a detail perspective view of one 35 of the links which connect the rings showing the method of construction, and

Fig. 3 is a view similar to Fig. 2, showing the link on the opposite side.

Referring to the drawings by characters of reference, 1 indicates the rings used in the construction of my improved seine fabric which are formed of any suitable metal and are preferably jointless, thereby eliminating 45 the danger of breaking. The material from which the rings 1 are formed is preferably circular in cross-section, as is clearly illustrated in the drawings.

The rings above described are secured to 50 each other by means of the links, indicated by the numeral 2, which are preferably formed of a single piece of wire and bent to form the bight portion 4 having at its terminals the parallel arms 5 and 6, each of

which is bent back as at 7 to form the hook 55 members illustrated in Figs. 2 and 3 of the drawings. These hook members are arranged to lie parallel with each other and in juxtaposition to form one end of the oval links by means of which the rings are connected together. The ends of the hook members are secured by means of a drop of solder designated by the numeral 3 or in any other suitable manner, but it is to be understood that when so desired, these ends may be left 60 free in order that additional rings may be placed in the oval links in order that the nets may be adjusted to different sizes.

It will be clearly seen that in forming my improved seine in this way the device is substantially indestructible, inasmuch as the seine is formed of metal which materially increases its strength and eliminates the danger of breakage, thereby considerably decreasing the expense usually entailed to keep 75 a seine of the ordinary character in repair.

When it is desired that the seine be increased in size a section formed in the same manner may be placed in position and owing to the peculiar shape of the links the rings 80 at the edge of the seine may be connected to the links at the edge of the attachable seine, as will be obvious from the foregoing description. The links forming the edge of the auxiliary seine are therefore left unsoldered or unwelded in order that the end rings may be slipped therebetween.

It is to be understood that the construction of the seine fabric described in the foregoing specification may be used for all types 90 of nets, traps, or set devices of any kind, which are at present in use by fishermen. It is to be understood further that the specific construction of the rings may be changed to suit the necessities of the user 95 and it may be deemed expedient to make said rings either hexagonal or octagonal.

While in the foregoing I have shown and described the preferred embodiment of my invention, I wish it to be understood that I 100 may change the specific arrangement of parts without in any way departing from the spirit and scope of my invention.

What I claim is:—

A net comprising a plurality of circular 105 bands or rings, a plurality of elongated oval connecting links, the body of the rings being movable in the links to increase the flexi-

bility of the net when assembled, each of
said rings being movable independently of
the net of the adjacent rings through the
oval connecting links, and the ends of the
oval connecting links being rigidly secured
to the body thereof to prevent accidental dis-
placement of the rings therefrom.

In testimony whereof I affix my signature
in presence of two witnesses.

FERNANDO G. MILLER.
